(57) **CLAIM**

The ornamental design for a meter for an integrated diagnostic test system, as shown and described.

DESCRIPTION

FIG. 1 is a front perspective view of our meter for an integrated diagnostic system;

FIG. 2 is a top view thereof;

FIG. 3 is a rear view thereof;

FIG. 4 is a left side view thereof;

FIG. 5 is a front view thereof; and,

FIG. 6 is a right side view thereof.

The bottom of our meter for an integrated diagnostic test system is not visible during normal use and does not form part of the claimed design. The broken lines in the figures are for illustrative purposes only and do not form part of the claimed invention.
